United States Patent Office.

HENRY KELLOGG, OF CHICAGO, ILLINOIS.

Design No. 3,993, dated April 26, 1870.

DESIGN FOR A TRADE-MARK.

The Schedule referred to in these Letters Patent and making part of the same.

to all whom it may concern:

Be it known that I, HENRY KELLOGG, of Chicago, the county of Cook and State of Illinois, have invented and produced a new and original Design for a Trade-Mark, of which the following is a specification. My design consists of a circular card or label, having in the center the picture of an eagle displayed, proper, with a shield upon its breast, and holding in its claws a scroll, that portion of the scroll upon the right having the words "The Drink," and that portion on the left, "of all Drinks."

This scroll extends beneath the eagle, and is there marked "1870."

A second scroll is held in the beak of the eagle, and bears the words, "Fountain of Health."

Above this scroll is a field of stars, surmounted by the word "Temperance," and around the edge of the card or label is described an annular border containing the words, "Kellogg's Hygienic Beer."

I claim as my invention—

The design for a trade-mark, described and shown.
HENRY KELLOGG.
